UNITED STATES PATENT OFFICE.

DAMON D. DUNKIN, OF GUION, ARKANSAS.

METHOD AND APPARATUS FOR GRADING MATERIAL.

Application filed September 27, 1927. Serial No. 222,262.

The present invention relates to an improved method and apparatus for grading materials and is designed primarily for the grading of relatively fine material, such for example as sand, although it is not necessarily restricted to such use.

An important object of the invention is to provide such a method and apparatus wherein the sand or other material to be graded 10 may be quickly and efficiently separated into a plurality of different grades, each grade containing grains of a relatively predetermined size.

Another object of the invention is to provide such a method and apparatus wherein the sand or other material to be graded is preferably deposited upon a traveling surface moving in an inclined plane, the inclination of said surface being such that those 15 grains of a relatively predetermined size are adapted to slide or roll freely thereover in the direction of their natural tendency and be discharged therefrom, while the remaining aggregation of finer mixed grains 20 are caused to adhere to said surface and be positively carried along therewith.

Another object of the invention is to provide such a method and apparatus of this nature wherein is provided a traveling conveyor 25 moving in a plurality of different planes, the conveyor being adapted to receive and carry the material to be graded in such a manner that that portion of the conveyor moving in each plane will effect the separation of a different, relatively predetermined grade therefrom.

Another object of the invention is to provide such a method and apparatus of this nature wherein is provided a preferably endless conveyor belt arranged to travel successively in a plurality of different planes, the belt being adapted to receive thereon and carry the material to be graded through said several planes in such a manner that that 45 portion of the belt moving in each plane will effect the separation of a relatively finer grade of material than that portion of the belt moving in the preceding plane.

A further object of the invention is to provide such a method and apparatus of this nature wherein the sand or other material to be graded is deposited upon a continuously moving conveyor belt including a plurality of material bearing surfaces having 55 different angles of inclination and traveling in different directions, each material

bearing surface being adapted to effect the separation of a relatively predetermined grade of material, the apparatus including means for adjusting the angles of inclination 60 of said material bearing surfaces.

A further object of the invention is to provide such a method and apparatus of this nature wherein is provided a conveyor belt including a plurality of inclined runs 65 having different angles of inclination and traveling in different directions, the sand or other material to be graded being deposited upon one of said runs in a manner that those grains of a relatively predetermined size will roll or slide downwardly thereover and be discharged therefrom, forming a finished grade or product, while the remaining aggregation of finer mixed grains will be caused to adhere to and be 70 carried along with said belt into the succeeding run wherein the process of separation is repeated to effect a separation of those grains of a relatively fine predetermined size, forming a second finished 75 grade or product.

Still another object of the invention is to provide such a method and apparatus of this nature wherein are provided a plurality of material bearing surfaces traveling 80 in different planes, each adapted to receive a mixed product to be graded, said surfaces being so arranged that those grains of material of a relatively predetermined size will be permitted to slide or roll freely thereover, 85 while the remaining material will be positively carried thereby.

Other objects and advantages of the invention will become more apparent during the course of the following description when taken in connection with the accompanying 95 drawings.

In the drawings forming a part of this application and wherein like numerals are employed to designate like parts throughout the same,

Fig. 1 is a longitudinal vertical section through grading apparatus constructed in accordance with the present invention, and

Fig. 2 is a section taken substantially on line 2—2 of Fig. 1.

In carrying out the present invention, there is provided a preferably endless conveyor belt arranged in substantially triangular formation and being trained about a plurality of rollers, said belt having a plurality of material bearing surfaces or runs

moving successively in an upwardly inclined plane, in a downwardly inclined plane and having different angles of inclination, which are variable. The sand or other material to be graded is ordinarily deposited initially upon that surface or run of the conveyor which is moving up the incline and preferably adjacent the upper end thereof. The angle of inclination of said surface or run is such that the coarser grains of a relatively predetermined size will freely slide or roll downwardly thereover in the direction of their natural tendency and be discharged from the lower end thereof, forming a finished grade or product, while the remaining aggregation of finer mixed grains are adapted to stick or adhere to the belt and be carried upwardly along therewith and into the downwardly moving run which is arranged at a different angle of inclination than the upwardly moving run. When the material traveling with or adhering to the belt passes into the downwardly moving run and thus meets a different angle of inclination, there is another separation, those grains of a relatively finer predetermined size being adapted to roll or slide downwardly over the belt and be discharged therefrom at the lower end thereof, forming a second finished grade or product, while the still finer mixed grains are caused to adhere to the belt and be carried along therewith. The material, still adhering to the belt after the second separation, is carried into the substantially horizontal run wherein the same will either fall off of the belt or can be removed therefrom by means of suitable brushes or the like, this material forming a third grade or product.

Referring now more in detail to the accompanying drawings, the numeral 5 designates in its entirety a suitable supporting framework comprising spaced horizontal base members 6 to which are secured, adjacent their opposite ends, the inclined members 7 and 8, said members converging upwardly and being pivotally connected as at 9 with the members 8 preferably extending beyond the members 7 to provide extensions 10. The members 8 are pivotally connected to the base members 6 as at 11 while the lower ends of the members 7 are adjustably secured to the base members by the fastening means 12. The base members 6 may be provided with a plurality or series of horizontally arranged openings 13 within which the fastening means 12 may be selectively engaged in order that the angles of inclination of the inclined members 7 and 8 may be varied as desired, it being noted that the members 6, 7 and 8 are arranged in substantially triangular formation.

The supporting framework 5 carries a plurality and preferably three transversely arranged rollers 14, 15 and 16, the rollers

14 and 16 being in substantial horizontal alignment with one another and carried by the inclined members 7 and 8 respectively, while the roller 15 is arranged at the apex of the framework and is carried by the extensions 10. The rollers 14, 15 and 16 are mounted respectively upon shafts 17, 18 and 19, the opposite ends of each shaft being journaled in bearings 20 carried by and slideable upon the base portions 21 of the members 22 secured to the corresponding portions of the framework, the bearings 20 being adjustable along the base portions 21 by means of adjusting screws 23 so that upon proper rotation of these screws, the rollers 80 may be moved in the desired direction to either tighten or loosen the conveyor belt 24.

This belt is of the preferably endless type and is trained about the rollers 14, 15 and 16, so that it is arranged in substantially triangular formation, said belt including a plurality of material bearing surfaces or runs 25, 26 and 27, the run 25 moving upwardly in an inclined plane, the run 26 downwardly in an inclined plane and the run 27 across 90 in a substantially horizontal plane. The angles of inclination of the runs 25 and 26 are adapted to be different and these angles may be varied, as found necessary to desirable, by proper adjustment of the members 7 in the manner above described. Any suitable width of belt may be used depending on the capacity and material to be graded and the said belt may be made of cotton ducking, silk, wool, or in fact of any other suitable fabric made of natural or synthetic material. The belt may also be made of either canvas or rubber.

The endless belt 24 is preferably positively driven in the direction indicated by the arrow in Fig. 1 with the inclined material bearing surfaces or runs being supported in their travel upon a plurality of supporting idler rolls 27'. In order to drive the belt, there may be secured to each of the roller shafts 17, 18 and 19, a sprocket wheel 28 about which is trained a sprocket chain 29 held tightened by means of an idler roller 30. Power to drive the belt may be transmitted initially to one of the shafts 115 from any suitable prime mover through the intermediary of a drive pulley or the like 31 shown as being secured to the roller shaft 18 although it may be secured to either the shaft 17 or 19 if preferred. Arranged at 120 the lower ends of the inclined runs of the belt are the receiving receptacles 32 and 33 while a receptacle 34 is also positioned beneath the substantially horizontal run 27.

The sand or other material to be graded 125 is contained within a feed box 35 suitably supported above the upwardly moving inclined run 25 of the belt adjacent the upper end thereof, said feed box having a slot or opening 36 in its bottom through which the 130

material is adapted to gravitate or fall onto the belt. The opening or slot 36 preferably extends substantially the entire width of the conveyor belt so that the material may 5 be uniformly fed thereto and is preferably controlled by means of a horizontal sliding plate 37 having an opening or slot 38 therein adapted to register with the opening or slot 36 in the bottom of the feed box when 10 it is desired to permit the material to pass therefrom onto the belt. When it is desired to shut off the supply of material, the plate 37 may be adjusted horizontally upon rotation of the adjusting screw 39 so as to 15 move the slot therein out of registry with the slot 36. Thus, the amount of material falling onto the conveyor belt may be effectively controlled and regulated. Of course, any other desired means may be provided for depositing the material upon the belt with or without fall so that the present invention is not to be restricted to the particular construction shown.

In operation, the sand or other material 25 to be graded is adapted to be fed from the feed box 35 onto the upwardly moving inclined run 25 of the belt adjacent the upper end thereof, the angle of inclination of said run being such that the coarser grains of 30 material of a relatively predetermined size will follow the path of their natural tendency and be permitted to freely slide or roll downwardly over the belt and be discharged at the lower end thereof into the receptacle 33, forming one finished grade or product. The rolling or sliding movement of the coarser grains will serve to agitate or cause a separation therefrom of the relatively finer mixed grains which will 35 settle to the bottom and as they come into contact with the belt will adhere thereto and be carried upwardly along therewith, over the roller 15, and then downwardly through the inclined run 26. The angle of inclination of the run 26 is different from that of the run 25 so that the material meeting a different inclination will cause another separation to take place, those grains of a relatively finer predetermined size being 40 caused to slide or roll downwardly over the belt and be discharged at the lower end thereof into the receptacle 32, forming a second finished grade or product, while the still finer grains will adhere to the belt and be carried therewith under the roller 14 into the substantially horizontal run 27. The grains of material which are carried with the belt into the horizontal run will 45 either drop therefrom into the receptacle 34 or can be removed by means of a suitable brush or scraper 40, if necessary. Thus, each succeeding run of the conveyor is adapted to 50 effect the separation of a relatively finer grade of material than the preceding run so that a coarse grade may be had, intermediate grades, and a fine grade.

While the present invention has been described hereinabove as primarily designed for the grading of sand, it is not necessarily restricted to such use since it may be employed for the separation of various kinds of material. For example, it may be used as a grader of any kind of material of the same specific gravity, making three grades of material according to the size of the particles or 55 grains of which the material is made. Also, it may be used as a grader of material of different specific gravity in which the different gravities are in different sizes of particles. For instance, in the separation of ore 60 of small size and one gravity from gangue of larger size and different gravity. Further, it may be utilized for effecting the separation of chaff and obnoxious seeds from grain, such as cockle-bur seed from 65 wheat.

It is to be understood that the form of the invention herewith shown and described is to be taken as the preferred embodiment of the same, and that various changes in the 70 shape, size and arrangement of parts may be resorted to without departing from the spirit of the invention or the scope of the subjoined claims.

Claims—

1. In apparatus for grading materials, a conveyor arranged to travel in a plurality of differently inclined planes, the material to be graded being deposited upon and carried by said conveyor in a manner that 75 that portion of the conveyor moving in each plane will effect the separation of a different relatively predetermined grade therefrom.

2. In apparatus for grading materials, a conveyor arranged to travel in a plurality of differently inclined planes, the material to be graded being deposited upon and carried by said conveyor in a manner that 80 that portion of the conveyor moving in each plane will receive a mixed product, the coarser grains of a different relatively predetermined size being adapted to slide or roll freely thereover, while the remaining finer material will be positively carried 85 thereby whereby that portion of the conveyor moving in each plane will effect the separation of a different grade of material.

3. In apparatus for grading materials, a conveyor belt arranged to travel successively 90 in a plurality of different planes, the material to be graded being deposited upon and carried by said belt in a manner that that portion of the belt moving in each plane will effect the separation of a different relatively predetermined grade therefrom, while conveying the remaining material into 95 the next succeeding plane.

4. In apparatus for grading materials, a conveyor belt arranged to travel successively in a plurality of different planes, the material to be graded being deposited upon and carried by said belt in a manner that that portion of the belt moving in each plane will receive a mixed product composed of relatively finer material than that product received by the preceding portion, the coarser grains of a relatively predetermined size upon each portion being adapted to slide or roll freely thereover and be discharged therefrom, while the remaining finer material will be caused to adhere thereto and be carried along therewith whereby each succeeding portion of the conveyor belt will effect the separation of a different grade of material.

5. In apparatus for grading materials, a conveyor belt arranged to travel successively in a plurality of different planes, the material to be graded being deposited upon and carried by said belt in a manner that that portion of the belt moving in each plane will effect the separation of a relatively finer predetermined grade of material than the preceding portion of the belt which travels in a different plane.

6. In apparatus for grading materials, a moving conveyor belt having a plurality of material bearing surfaces traveling in different planes, each surface being adapted to receive a mixed product to be graded, said surfaces being so arranged that those grains of material of a relatively predetermined size will be caused to slide or roll freely thereover, while the remaining material will be positively carried thereby whereby each succeeding material bearing surface will effect the separation of a relatively finer grade of material than the preceding surface.

7. In apparatus for grading materials, a moving conveyor belt including a plurality of material bearing runs having different angles of inclination, and means for depositing the material to be graded upon said belt in a manner that each material bearing run is adapted to effect the separation of a different relatively predetermined grade therefrom.

8. In apparatus for grading materials, a traveling conveyor belt including a plurality of material bearing runs having different angles of inclination, said belt being adapted to receive and carry the material to be graded in a manner that each material bearing run is adapted to effect the separation of a relatively predetermined grade of material therefrom, each material bearing run serving to effect the separation of a relatively finer grade of material than the preceding run.

9. In apparatus for grading materials, a traveling conveyor belt including a plurality

of material bearing runs having different angles of inclination, each of said runs being adapted to receive a mixed product to be graded, the angles of inclination thereof being such that the coarser grains of a relatively predetermined size will roll or slide freely thereover and be discharged therefrom, while the remaining finer material will be caused to adhere thereto and be carried along therewith whereby each material bearing run will effect the separation of a different grade of material.

10. In apparatus for grading materials, a traveling conveyor belt including a plurality of material bearing runs having different angles of inclination, each run being adapted to receive thereon a mixed product to be graded, the angles of inclination of said runs being such that the coarser grains of a relatively predetermined size roll or slide downwardly thereover and be discharged therefrom, forming a finished grade or product, while the remaining aggregation of finer mixed grains will be caused to adhere thereto and be carried along therewith, whereby each succeeding material bearing run will effect the separation of a relatively finer grade of material than the preceding run, and means for adjusting the angles of inclination of said runs.

11. In apparatus for grading materials, a traveling conveyor belt including a plurality of material bearing runs having different angles of inclination, and means for depositing the material to be graded upon one of said runs adjacent the upper end thereof, the angle of inclination of said run being such that the coarser grains of a relatively predetermined size will slide or roll freely thereover and be discharged therefrom, forming a finished grade or product, while the remaining aggregation of finer mixed grains will be caused to adhere thereto and be carried along therewith into a second run, the angle of inclination of said second run being such that the grains of a relatively finer predetermined size will slide or roll downwardly thereover and be discharged therefrom, forming a second finished grade or product, while the still finer grains will adhere to said run and be carried along therewith to form a third grade or product.

12. In apparatus for grading materials, a traveling conveyor belt having a pair of material bearing runs arranged at different angles of inclination, one run traveling upwardly in an inclined plane and the other downwardly in an inclined plane, means for depositing the material to be graded upon the upwardly moving run adjacent the upper end thereof, the angle of inclination of said run being such that the coarser grains of material of a relatively predetermined size will slide or roll downwardly thereover

and be discharged at the lower end thereof, forming one finished grade or product, the remaining aggregation of finer mixed grains being caused to adhere to the run and be carried upwardly along therewith and over into the downwardly moving run, the angle of inclination of this run being different from that of the first run and such that those grains of a relatively finer predetermined size will slide or roll downwardly thereover and be discharged at the lower end thereof, forming a second finished grade or product, while the remaining finer material will adhere to said second run and be carried along therewith to form a third grade or product.

13. In apparatus for grading materials, an endless traveling conveyor belt having a plurality of material bearing runs arranged in substantially triangular formation and moving upwardly in an inclined plane, downwardly in an inclined plane and then across in a substantially horizontal plane, and means for depositing the material to be graded upon the upwardly moving run adjacent the upper end thereof, the angle of inclination of said run being such that the coarser grains of a relatively predetermined size will roll or slide downwardly thereover and be discharged from the lower end thereof, forming a finished grade or product, the remaining aggregation of finer mixed grains being caused to adhere to said run and be carried along therewith into the downwardly moving run, this run having a different angle of inclination than the upwardly moving run so that those grains of a relatively finer predetermined size will slide or roll downwardly thereover and be discharged from the lower end thereof, forming a second finished grade or product, while the remaining finer material will adhere to said run and be carried into the substantially horizontal run, forming a third grade or product.

14. The method of grading materials, which consists in providing a traveling surface moving in differently inclined planes, depositing the material to be graded upon that portion of the surface moving in one plane in a manner that the coarser grains of material of a relatively predetermined size will move freely thereover and be discharged therefrom, while the remaining finer mixed grains will be positively carried thereby into a differently inclined plane where those grains of a relatively finer predetermined size will move freely over the surface and be discharged therefrom, while the still finer material will be positively carried thereby.

15. The method of grading materials, which consists in depositing the material to be graded upon a traveling surface moving in an inclined plane, adjusting the angle of inclination of said surface so that the coarser grains of material of a relatively predetermined size will slide or roll freely thereover and be discharged therefrom, forming one grade of product, while the remaining finer mixed material will be caused to adhere thereto, passing the mixed material adhering to the surface into a differently inclined plane, the angle of inclination of the surface in the second plane being such that those grains of a relatively finer predetermined size will slide or roll freely thereover and be discharged therefrom, forming a second grade or product, while the remaining still finer material will adhere thereto and be carried therewith forming a third grade or product.

16. The method of grading materials, which consists in providing a traveling surface moving upwardly in an inclined plane and then downwardly in a differently inclined plane, depositing the material to be graded upon that portion of the surface moving up the incline in a manner that the coarser grains of material of a relatively predetermined size will move freely thereover and be discharged therefrom, forming one grade or product, while the remaining finer mixed grains of material will be positively carried thereby into the downwardly moving plane where those grains of a relatively finer predetermined size will move freely over the surface and be discharged therefrom, forming a second grade or product, while the still finer material will be positively carried therewith forming a third grade or product.

17. The method of grading materials, which consists in depositing the material to be graded upon an upwardly moving inclined surface, adjusting the angle of inclination of said surface so that the coarser grains of material of a relatively predetermined size will roll or slide downwardly thereover and be discharged therefrom, forming one grade or product while the remaining finer mixed material will be caused to adhere thereto, passing the material adhering to the surface into a downwardly moving inclined plane, the angle of inclination of the surface in the second plane being such that those grains of a relatively finer predetermined size will roll or slide downwardly thereover and be discharged therefrom, forming a second grade or product, while the remaining still finer material will adhere thereto and be carried therewith forming a third grade or product.

18. The method of grading materials, which consists in depositing the material to be graded upon a traveling surface having a plurality of material bearing portions moving in different planes, each portion being adapted to receive a mixed product and to separate therefrom the grains of a relatively

predetermined size whereby each portion of the surface will effect the separation of a different grade of material.

19. The method of grading materials, which consists in depositing the material to be graded upon a traveling surface having a plurality of material bearing portions moving in differently inclined planes, and in adjusting the angles of inclinations of the portions in a manner that each of said portions will effect the separation of a relatively finer predetermined grade of material than the preceding portion.

20. The method of grading materials, which consists in depositing the material to be graded upon a traveling surface having a plurality of material bearing portions moving in differently inclined planes, each portion being adapted to receive a mixed product, and in adjusting the angles of inclination of said portions in a manner that the grains of a relatively predetermined size will slide or roll thereover and be discharged therefrom while the remaining finer material will be caused to adhere thereto and be carried therewith whereby each material bearing portion will effect the separation of a different grade of material.

21. In apparatus for grading sand and like materials, including a supporting framework of substantially triangular formation comprising spaced horizontal base members and a pair of upwardly converging side members carried by each base member and pivotally connected adjacent their upper ends, one of the inclined members of each pair being pivotally connected at its lower end to the respective base member and the lower end of the other inclined member of the pair being adjustably associated with said base member whereby the same may be moved horizontally with respect thereto to vary the angles of inclination of said side members, a pair of rollers carried by the opposed side members adjacent the base of the framework and arranged in substantially horizontal alignment with one another, a third roller arranged at substantially the apex of the framework and positioned between the first named rollers, an endless belt trained about the three rollers, sprockets associated with said rollers, a sprocket chain trained about said sprockets for driving the same together with said rollers whereby to cause the belt to move upwardly in an inclined plane, downwardly in a different inclined plane and across in a substantially horizontal plane, means for depositing the material to be graded upon the head of that portion of the belt moving upwardly, a receptacle arranged at the foot of each inclined portion of the belt, and a receptacle arranged beneath the substantially horizontal portion of said belt.

apex of the framework and positioned between the first named rollers, an endless belt trained about the three rollers and adapted to move upwardly in an inclined plane, downwardly in a different inclined plane and across in a substantially horizontal plane, and means for depositing the material to be graded upon the head of that portion of the belt moving upwardly.

22. In apparatus for grading sand and like materials, including a supporting framework of substantially triangular formation comprising spaced horizontal base members and a pair of upwardly converging side members carried by each base member and pivotally connected adjacent their upper ends, one of the inclined members of each pair being pivotally connected at its lower end to the respective base member and the lower end of the other inclined member of the pair being adjustably associated with said base member whereby the same may be moved horizontally with respect thereto to vary the angles of inclination of said side members, a pair of rollers carried by the opposed side members adjacent the base of the framework and arranged in substantially horizontal alignment with one another, a third roller arranged at substantially the apex of the framework and positioned between the first named rollers, an endless belt trained about the three rollers, sprockets associated with said rollers, a sprocket chain trained about said sprockets for driving the same together with said rollers whereby to cause the belt to move upwardly in an inclined plane, downwardly in a different inclined plane and across in a substantially horizontal plane, means for depositing the material to be graded upon the head of that portion of the belt moving upwardly, a receptacle arranged at the foot of each inclined portion of the belt, and a receptacle arranged beneath the substantially horizontal portion of said belt.

Signed at Guion, in the county of Izard and State of Arkansas, this 23d day of September, 1927.

DAMON D. DUNKIN.

CERTIFICATE OF CORRECTION.

Patent No. 1,699,522.

Granted January 22, 1929, to

DAMON D. DUNKIN.

It is hereby certified that error appears in the printed specification of the above numbered patent requiring correction as follows: Page 3, line 112, claim 2, strike out the word "different"; page 4, line 85, claim 10, after the word "size" insert the word "will"; and that the said Letters Patent should be read with these corrections therein that the same may conform to the record of the case in the Patent Office.

Signed and sealed this 19th day of February, A. D. 1929.
